US0D1021023S

(12) **United States Design Patent** (10) **Patent No.:** **US D1,021,023 S**
(45) **Date of Patent:** **** Apr. 2, 2024**

(54) **TOILET**

(71) Applicant: **Ning Xu**, Shanghai (CN)

(72) Inventor: **Ning Xu**, Shanghai (CN)

(**) Term: **15 Years**

(21) Appl. No.: **29/837,754**

(22) Filed: **May 9, 2022**

(51) **LOC (14) Cl.** **23-02**

(52) **U.S. Cl.**

USPC **D23/299**; D23/297; D23/298

(58) **Field of Classification Search**

USPC D23/296-299, 273-274, 295, 309,

D23/311-312; D32/37; D3/305;

D24/123; D7/512

CPC A47K 13/005; A47K 17/026; A47K 13/02;

A47K 13/00; A47K 13/04; A47K 13/08;

A47K 13/06

See application file for complete search history.
